UNITED STATES PATENT OFFICE

HUBERT C. HART, OF UNIONVILLE, CONNECTICUT.

IMPROVEMENT IN BIT-STOCKS.

Specification forming part of Letters Patent No. 149,306, dated April 7, 1874; application filed
February 27, 1874.

To all whom it may concern:

Be it known that I, HUBERT C. HART, of Unionville, in the county of Hartford and State of Connecticut, have invented certain new and useful Improvements in Bit-Stocks, of which the following is a specification, reference being had to the accompanying drawings, where—

Figure 1 is a view of the whole bit-stock. Fig. 2 is a view of the clamp or chuck in central vertical section. Fig. 3 is a view of the mouth of the chuck.

The invention consists in a combination of parts whereby the bit is securely clamped in the stock and readily detached therefrom.

The letter *a* indicates the main part or body of the bit-stock; *a'*, the button on the upper end of the same. To the lower end of the part *a* is attached the chuck-shell *b*, into the upper end of which runs the thumb-screw *c*, the screw-thread on its lower end taking into the nut *d*, to which are pivoted the jaws *e e*, which are fitted on their opposing faces to grasp and hold the shank of an auger-bit. The spring *f* serves to press the nut and the jaws constantly downward and outward. The jaws are held from turning in the shell *b* by

the pin *e'* projecting from one of the jaws into the mortise *b'* in the shell. The mouth of the shell at *g* is made with a flare, and the jaws have a corresponding swell, so that as the jaws are moved inward by means of the thumb-screw they will be pressed together, and when moved outward, the jaws are permitted to open, being pressed apart by the spring *h*. The shank of the bit is introduced between the jaws while they are opened, and then, by means of the thumb-screw, the hold of the jaws upon the bit is tightened.

I claim as my invention—

1. In combination with the body *a* and shell *b*, the clamping jaws *e e* hinged in the nut *d* and made to operate, both at the same time, by means of the screw *c*, all constructed, arranged, and designed for operation and use, substantially as shown and described.

2. In combination with the jaws *e e*, the projection *e'*, made to operate within the slot *b'* in the shell *b*.

H. C. HART.
